UNITED STATES PATENT OFFICE.

THOMAS C. STEWARD, OF CHATTANOOGA, TENNESSEE.

CAR-COUPING ATTACHMENT.

SPECIFICATION forming part of Letters Patent No. 236,855, dated January 18, 1881.

Application filed October 12, 1880. (No model.)

To all whom it may concern:

Be it known that I, THOMAS CORWIN STEWARD, of Chattanooga, in the county of Hamilton and State of Tennessee, have invented a new and Improved Car-Coupling Attachment, of which the following is a specification.

The object of my invention is to provide a new and improved car-coupling attachment which is simple in construction, convenient in use, and permits of coupling cars by means of the well-known link and draw-head, without requiring the operator to enter in between the cars and endanger his life, as has been necessary heretofore, for he can stand at the side 10 of the car while coupling with my improved attachment, which he does with one hand, and with the other lie can give his signal to the engineer.

The invention consists of a bar provided 20 with an adjustable handle, which bar is pivoted adjustably, both longitudinally and in height, to a vertical rod, which is adjustably held in a frame attached to the end of a car platform or floor, this bar being thus so 25 adjustable that it can catch under the link of a draw-head of a car of any desired size, style, or construction, and lift the link so that it can enter the draw-head of the next car.

In the accompanying drawings, Figure 1 is 30 a perspective view of the end of a car provided with my improved car-coupling attachment. Fig. 2 is a longitudinal sectional elevation of the bracket-frame attached to the end of the car platform or floor.

35 A bar, A, provided at the outer end, B, with a handle, C, that can be adjusted by means of the apertures D and bolts E, to make the bar A a certain distance longer or shorter, is pivoted in such a manner that its inner end, 40 F, reaches under the link G, held in a draw-head H, by a link-pin, J, so that the outer end of this link G can be raised by depressing the outer end, B, of the bar A.

In order to adjust the fulcrum of the bar A 45 as necessity may require, it is provided with a series of apertures, K K, near the middle. A pin, L, passes through one of these apertures into one of a series of apertures, M, in a rod, N, which is held between the arms O 50 O of a bracket-frame, P, attached to the end

of the car platform or floor Q, as shown. These arms O O are provided with apertures R R near the outer end, to admit of adjusting the rod N a greater or less distance from the end of the car platform or floor Q. This 55 rod N is held in its desired position by means of the nuts S S. The bar A has a bend, T, beyond the rod N, so that the end F of the bar A can reach beyond the draw-head, but does not require the bracket-frame P to project out very far. The bar A can swing on the pin L as a pivot, or on the rod N as a pivot.

The operation is as follows: The link is secured in one of the draw-heads H by means 65 of the pin J, as shown, in the ordinary manner. The operator steps to the side of the track and inclines the bar A to such an extent that its inner end, F, will be below the link G, and swings the bar forward and backward until he has the end F of the bar A in the desired position in regard to the length of the link, the rod N forming the axis of rotation. The operator then depresses the handle C, thereby raising the link G proportionately until the latter is in such a position that it passes into the draw-head of the approaching car. The pin can be dropped from above or can be set so that it drops by the shock. The cars can thus be conveniently and rapidly coupled without requiring the operator to pass in between the cars and endanger his life.

The bar A can be adjusted to suit any car, and the whole device can be attached to old 85 cars without altering them, and as the apparatus can be adjusted for any car only one size need be used.

Having thus described my invention, I claim as new and desire to secure by Letters Patent—

The combination, with the draw-head H, of the bar A, having bend T and apertures K, the vertical rod M, having apertures N, and the arms O, having apertures R, as and for the 95 purpose specified.

THOMAS CORWIN STEWARD.
